UNITED STATES PATENT OFFICE

WILLIS H. CARRIER, OF ESSEX FELLS, NEW JERSEY, AND EDWARD S. LEA, OF MORRISVILLE, PENNSYLVANIA, ASSIGNEES, BY MESNE ASSIGNMENTS, TO CARRIER RESEARCH CORPORATION, OF NEWARK, NEW JERSEY, A CORPORATION OF NEW JERSEY

HEAT EXCHANGE DEVICE AND METHOD OF MAKING THE SAME

Application filed December 28, 1930. Serial No. 504,678.

This invention relates to heat exchange devices, such as steam radiators or heaters, of the sort which comprise a core or body having fluid passages for the steam or other temperature changing medium, usually provided with projecting radiating fins or plates, and one or more headers with which the fluid passages connect, and by which the several passages of the core communicate with the pipe or pipes for the supply and discharge of the steam or other medium to and from said passages.

More particularly, the invention relates to an improved construction and method of making the same, for radiators or heaters in which the fluid passages and the radiating fins or plates are made of relatively thin steel or other metal which is apt to corrode or rust if not properly protected, and in which the headers or elements with which the fluid passages connect are made with walls of sufficient thickness to withstand high steam pressures and the ravages of corrosion or rust.

Steam radiators or heaters have been made in which the core or body of finned fluid passages is built up of a multiplicity of thin, spaced sheets or plates, each having holes therethrough surrounded by integral flanges or nipples projecting from one side of the sheet or plate, the projecting flanges or nipples of the several plates being nested or fitted tightly and brazed one within another so that the nipples or flanges thus fitted and secured together form the fluid passages, and the plates form extended radiating fins or surfaces projecting out from the walls of the fluid passages of the radiator or heater. Such radiators or heaters have been made of thin steel sheets, the nested, tapering nipples of which are brazed together by means of copper which is melted at a high temperature in a hydrogen atmosphere. This method produces good bonds between the interfitting nipples forming the fluid passages, but the interior surfaces of these passages are not adequately protected against corrosion or rusting and it has been found necessary, in order to insure long life of the radiators or heaters to line the passages with thin tubes of a non-corrodible metal, such as lead,

which lead tubes are drawn through the fluid passages and extruded or expanded tightly against the interior surfaces of the passages. Difficulty has also been found in making joints or connections between the thin walls of the fluid passages and headers that will reliably withstand high steam pressures.

The present invention provides a practical construction and method for joining radiator or heater cores of the type last mentioned to the headers and preventing corrosion of the parts. However, the invention is not necessarily restricted to radiators or heaters in which the fluid passages are built up as explained, by interconnected flanges or nipples of the thin fin plates, but is also applicable to devices of other construction, for instance to devices involving thin, single-piece or continuous tubes, similarly lined to a header or analogous element.

One object of the invention is to produce practical, strong durable and reliable joints between lined tubes, passages or elements of relatively thin metal and a header or element of relatively thick metal, and which will insure a perfect sealing of the joints between the linings and the lined walls and prevent the possibility of leakage of steam or moisture between the linings and the passage walls so as to cause corrosion or rusting of the walls.

Other objects of the invention are to provide a practical method for making strong, durable and reliable joints between the elements of heat exchange devices and hermetically sealing the joints between the walls and wall linings of the devices; also to improve heat exchange devices and the method of making same in the other respects herein-after described and set forth in the claims.

In the accompanying drawing:

Fig. 1 is a sectional elevation of a steam heater embodying our invention.

Fig. 2 is a fragmentary side elevation thereof.

Fig. 3 is a fragmentary, sectional plan view thereof on line 3-3, Fig. 1.

Fig. 4 is an enlarged detail section showing the ferrule connections between one header and body at one end of the heater.

Referring first to the construction illustrated in Figs. 1 to 4, the core or finned tube body of the radiator or heater is composed of a plurality of relatively closely spaced radiating plates 10, each of which plates is provided with a plurality of holes surrounded by flanges or nipples 11 integral with the plate, projecting from one side of the plate. These flanges 11 are slightly tapered or conical and the flanges of one plate fit tightly into the flanged holes of the next plate so that when the plates are thus secured together the interfitting flanges form continuous tubes or passages surrounded by the plates which project laterally from the tubes or passages and form extended radiating fins or surfaces. The joints between the interfitting flanges 11 are preferably brazed by means of copper in a hydrogen atmosphere, as explained. Preferably the tubes or passages thus formed are arranged in two or more rows with the tubes in one row staggered with reference to the tubes in the next row, and the tubes are preferably elongated or elliptical in cross section, as shown.

12 and 13 represent opposite or supply and discharge headers connected to the opposite ends of the finned tubes. These headers are preferably alike and each is composed of thick-walled, inner and outer portions or sections 14 and 15, which may be made of steel. The inner section of the header 12 is provided with integral, inwardly projecting flanges or nipples 16 into which the ends of the nipples 11 on the adjacent fin plate are pressed and brazed by the same operation that is employed to press and braze together the flanges of the several plates. The walls of the header are of sufficient thickness to withstand high steam pressure and also to insure long life under usual conditions of corrosion, and are thicker than the sheets of which the core is composed, but the internal dimensions and shape of the inturned nipples 16 of the header correspond to the external dimensions and taper of the nipples of the fin plates so that the ends of the tubes or fluid passages formed thereby properly fit the nipples of the header. The header is preferably brazed on the ends of the tubes in the same manner and at the same time so that the flanged fin plates are brazed to each other.

The inner section or portion 14 of the opposite header 13 is of the same form and has similar inwardly projecting nipples or flanges 16 forming tapered holes, but since the fin plate nearest to this header has no flanges or nipples projecting toward the header, a separate ferrule or sleeve 17 is employed to connect each of the core tubes or passages with this second header 13. Each of these ferrules 17 is preferably of double tapered or double conical form and has thin walls corresponding substantially in thickness, dimensions and taper to the flanges on

the fin plates and has one end fitted and brazed in one flanged hole of the adjacent fin plate and projects outwardly from the plate similarly to the nipples on the fin plate at the opposite end of the core. These projecting ends of the ferrule 17 are adapted to fit into and be brazed in the flanged hole of the second header 13 in the manner above described in connection with the hole flanges on the first fin plate.

After the inner sections or portions of the headers have thus been brazed or attached to the opposite ends of the core tubes or passages, thin tubes 18, preferably of lead, are drawn through the tubes or passages of the core and expanded against the inner surfaces of the tubes or passages so as to tightly fit and conform to the same and to be extruded into all recesses. The projecting ends 18a of the lining tubes are then turned or folded over the inwardly projecting flanges 16 of the headers and tightly against the outer surfaces of flanges 16. The joints between these turned-over ends 18a of the lining tubes and the header flanges 16 are then hermetically sealed, preferably by solder, shown at 19. The inwardly projecting flanges 16 and the peripheral walls 20 of the headers form wells or depressions so that by placing the core with headers attached in an upright position with one header uppermost and horizontal depressions are provided in the uppermost header in which the solder can be placed, and then by heating the header to the required temperature, the solder will flow and fuse to the overturned ends of the lining tubes and form hermetic or steam-tight joints between the tube linings and the headers, which will prevent steam or moisture from entering between the linings and the walls of the tubes through which the linings pass. The joints between the opposite header and the adjacent ends of the lining tubes are similarly sealed by turning the core upside down and placing the solder in the then uppermost header.

The outer sections or portions 14 of the headers can be welded or brazed to the inner portions 15 in the usual or any suitable manner.

In the construction described, the radiating tubes may be made of thin sheet metal or metal which may corrode or rust, but the linings sealed to the headers, as explained, prevent the possibility of moisture getting between the linings and the walls of the tubes so as to reach and attack the metal of the tubes. There is no strain upon these lining elements, the brazed joints between the ends of the tubes or passages and the hole flanges of the headers taking the strain and affording the necessary mechanical strength.

We claim as our invention:

1. A heat exchange device comprising a header having a hole in a wall thereof sur-

- rounded by an integral wall flange projecting into said header, a passage-forming element rigidly secured in said hole, a lining of non-corrodible material extending through 5 said element and having its end portion turned over said inwardly projecting flange, and a body of material hermetically sealing the joint between the end of said lining and said header flange.
- 10 2. A heat exchange device comprising a header having a hole in a wall thereof surrounded by an integral wall flange projecting into said header, a passage-forming element rigidly secured in said hole, a lining of 15 non-corrodible material extending through said element and having its end portion turned over said inwardly projecting flange, and a body of metal into which the end of said lining extends and which is fused to 20 said end and header wall and seals the joint between the end of said lining and said header flange.
3. A heat exchange device comprising an element having a relatively thick wall provided with a hole surrounded by an integral wall flange, a hollow element having relatively thin walls of corrodible metal forming a fluid passage and fitting in said hole and brazed to said flange, a corrosion-resisting 25 metal lining extending through said hollow element, and a body of metal into which the end of said lining extends and which is fused to said end and to said thick wall and seals the joint between the end of said lining and 30 said flange.
4. A heat exchange device comprising an element having a relatively thick wall of corrodible metal provided with a hole therethrough, an element having relatively thin 35 walls of corrodible metal forming a fluid passage and fitting in said hole and brazed to said thick wall, a corrosion-resisting metal lining said fluid passage, and a body of metal into which the end of said lining extends and 40 which is fused to said end and to said thick wall and seals the joint between the lining and the walls of said passage.
5. A heat exchange device comprising a body composed of spaced relatively thin 45 plates having holes surrounded by flanges, the flanges of the several plates fitting and being secured one within another thereby forming fluid passages, a relatively thick walled header having holes surrounded by 50 flanges in which the flanges at one end of said body are rigidly secured, a second similarly flanged header at the opposite end of said body, and ferrules fitting and brazed in the flanges of said second header and of the 55 adjacent body plate.
6. A heat exchange device comprising a body composed of spaced plates having holes surrounded by flanges, the flanges of the several plates fitting and being brazed one with- 60 in another thereby forming fluid passages,
- headers at opposite ends of said body, each having holes surrounded by inwardly projecting flanges, the flanges of the plate at one end of said body fitting and being brazed in the flanges of one of said headers, and ferrules fitting and being brazed in the flanges of said other header and of the adjacent body plate.
7. A heat exchange device comprising a body having spaced relatively thin radiating plates of metal and fluid passages formed by connected integral parts of said plates, the passage-forming parts of the plate at one end of said body projecting outwardly from said plate, a header having walls of greater thickness than said plates and provided with holes surrounded by inwardly projecting flanges in which said passage-forming parts of said end plate are secured, a second similar header at the opposite end of said body, ferrules secured in the flanged holes of said second header and entering and secured in the adjacent ends of said fluid passages, said passages being lined with corrosion-resisting metal, and solder sealing the joints between the ends of said linings and the walls of said passages at their opposite ends.
8. The method of making a heat exchange device formed with a radiating body having spaced thin plates of metal and fluid passages formed by connected integral parts of said plates, and headers having relatively thicker walls and communicating with the opposite ends of said fluid passages, said method consisting in forming holes in the walls of said headers surrounded by integral wall flanges, brazing the passage-forming parts at one end of said body in the flanged holes of one header, brazing ferrules in the flanged holes of the other header and in the adjacent ends of said fluid passages, lining said fluid passages with a corrosion-resisting metal, and sealing the joints between the ends of said linings and said fluid passages by solder fused to the ends of the linings and the adjacent walls of the headers.
9. The method of making a heat exchange device formed with a radiating body having spaced thin plates of metal and fluid passages formed by connected integral parts of said plates, and headers having relatively thicker walls and communicating with the opposite ends of said fluid passages, said method consisting in forming holes in the walls of said headers surrounded by integral wall flanges, brazing the passage-forming parts at one end of said body in the flanged holes of one header, brazing ferrules in the flanged holes of the other header and in the adjacent ends of said fluid passages, inserting seamless lining tubes of a corrosion-resisting metal in said fluid passages, extruding said lining tubes into close contact with the walls of said fluid passages, turning the ends of said lining tubes

over the ends of said hole flanges of the headers, and forming bodies of solder in said headers fused to the ends of said lining tubes and to said headers to seal the joints between
5 the lining tubes and the walls of said fluid passages.
